UNITED STATES PATENT OFFICE.

ARTHUR LAMBERT BARBER, OF HECKMONDWIKE, ENGLAND.

PENHOLDER FOR RULING-MACHINES.

1,068,298.

Specification of Letters Patent. Patented July 22, 1913.

Application filed December 16, 1911. Serial No. 666,221.

To all whom it may concern:

Be it known that I, ARTHUR LAMBERT BARBER, subject of the King of Great Britain, residing at 21 George street, Heckmondwike, Yorkshire, England, have invented certain new and useful Improvements in Penholders for Ruling-Machines, of which the following is a specification.

This invention relates to penholders for 10 ruling machines, and refers particularly to holders wherein each pen with the penholder proper is adapted to be adjustably raised or lowered by sliding on the part of its main carrier usually termed the extension. In 15 penholders of this form it has hitherto been customary to arrange a turn or bend, on which the penholder proper slides, below the extension or main carrier, an adjusting screw being adapted to engage a part of the 20 sliding member on such turn or bend. This position or arrangement of the penholder proper is found to interfere with the required practice of passing ink supplying flannels through or over such penholders 25 and the main object of the present invention is to overcome this disadvantage.

According to the invention the extension end is turned or adapted to project upwardly from the front of the extension or 30 main carrier, the slide member together with its adjustment mechanism being mounted thereon above the extension part of the main carrier as hereinafter described. By this arrangement the carrying and 35 adjustment mechanism of the pen proper does not interfere in any way with the carrying of the ink flannels.

Referring now to the accompanying 40 drawings which show one convenient form of device constructed according to the invention:—

Figure 1 shows an extension or main carrier complete with its penholder slidingly mounted thereon. Fig. 2 is an enlarged 45 part sectional view showing more clearly the penholder mounted on the extension. Figs. 3 and 4 are elevation and plan views respectively of part of the extension, and Fig. 5 is a sectional plan view of the same 50 on line 5, 5. Fig. 6 is an enlarged view showing the top part of the penholder, and Fig. 7 is a sectional plan view of the same 55 on line 7, 7.

The end *a* of the extension or main carrier *b* is turned upwardly as shown and slidably mounted thereon is the upper end

c of the penholder *d*. The extension *b* and the bend *a* are preferably formed by a flanged metal strip stamped out of a flat piece for simplicity in manufacture, and at 60 the upper end of the bend the strip is bent into a bow shape *e* for a purpose which will hereinafter appear.

The upper end *c* of the penholder is formed of two portions, viz., the stamped 65 out strip *f* having the flanges *g* adapted to embrace the outside of the member *a* so as to slide thereon and the inner strip *h* also having flanges *l* adapted to engage the inside of the flanges *m* of the member *a* so as 70 to secure a firm seating and steady sliding of the member *c* on the member *a*. The flanges *g* are provided with lugs *n* adapted to be bent around behind the member *a*. To adjust the slideway part *c* a screwed 75 spindle *o* (see particularly Fig. 2) is adapted to engage a screw thread in the doubled over horizontal portion *p* of the strips *f* and *h*, such horizontal portion being situated in vertical alinement with the member 80 *a*. The upper end of the screw *o* is provided with a milled or like operating head *q* and a collar *r* adapted to engage the bow *e* as shown so as to prevent longitudinal movement of said screw. By rotating the 85 screw the pen is readily adjusted.

The upper portion of the inclined part of the penholder *d* is narrowed at *s* as shown in Fig. 7, so that feeding wools or flannels may be passed to inkwells between the 90 spaces thus left between each two adjacent pens. This allows of the pens being arranged closely together and yet permits the feeders to be conveniently passed through. The pen is preferably stamped with a 95 strengthening rib at this part as shown by *t*.

What I claim as my invention and desire to secure by Letters Patent is:—

1. In penholders for ruling machines, the combination of a main carrier, a member 100 projecting vertically upward therefrom, a member slidably mounted on said upwardly projecting member and having a horizontal portion situated in vertical alinement with said upwardly projecting member, 105 a screw adapted to screw into said horizontal portion, and a collar and operating head on said screw engaging the upper end of the upwardly projecting member to prevent longitudinal movement of the screw. 110

2. In penholders for ruling machines, the combination of a horizontal main carrier

formed of a channel section with flanges and having a vertical upward bend of similar section at its forward end, a pen-carrying member formed at its upper end with flanges engaging inside and outside the flanges of said vertical upward bend so as to slide thereon, a bowed upper end on the top of said upward bend, a screw having an operating head engaging the upper side of said bowed end and a collar engaging the

underside thereof, and a horizontal portion on the top of said sliding member with which said screw engages.

In testimony whereof I have signed my name to this specification in the presence of 15 two subscribing witnesses.

ARTHUR LAMBERT BARBER.
